CLAIM

I claim the ornamental design for a container and lid therefor, as shown and described.

DESCRIPTION

FIG. 1 is an isometric top view of the assembled lid and container.

FIG. 2 is a left hand end view thereof.

FIG. 3 is a right hand end view thereof.

FIG. 4 is a front view thereof.

FIG. 5 is a rear view thereof.

FIG. 6 is a plan view thereof.

FIG. 7 is a bottom view thereof.

FIG. 8 is an isometric top exploded view thereof.

FIG. 9 is an isometric bottom exploded view thereof.

FIG. 10 is a left hand end view of the lid for use with the container.

FIG. 11 is a right hand end view thereof.

FIG. 12 is a front view thereof.

FIG. 13 is a rear view thereof.

FIG. 14 is a plan view thereof.

FIG. 15 is a bottom view thereof.

FIG. 16 is an isometric top view thereof.

FIG. 17 is a left hand end view of the container for use with the lid.

FIG. 18 is a right hand end view thereof.

FIG. 19 is a front view thereof.

FIG. 20 is a rear view thereof.

FIG. 21 is a plan view thereof.

FIG. 22 is a bottom view thereof; and,

FIG. 23 is a top isometric view thereof.

The container's body and the lid are shown alone for convenience of illustration only.
